SHIPPING CONTAINER

Frank Ditchfield, Cleveland, Ohio, assignor to
The Youngstown Steel Door Company, Cleve-
land, Ohio, a corporation of Ohio

Application July 9, 1940, Serial No. 344,545

11 Claims. (Cl. 221—144)

This invention relates to shipping containers and more particularly to containers for the transportation of bulk materials.

It is an object of this invention to provide containers for shipment of bulk materials having closures for the discharge openings of the containers capable of controlling the flow of material and also of quickly releasing the material to permit rapid discharge thereof.

A further object is to provide containers for the shipment of bulk materials of varying sizes having closures for the discharge openings of the containers constrained to initial sliding movement for controlling the flow of material of small size where desired and capable of swinging movement to permit a rapid discharge of material.

A further object is to provide containers for shipment of bulk materials having closures for the discharge openings of the containers constrained to sliding movement during final closing movement wherein sliding movement of the closures is automatically insured.

A further object is to provide containers for the shipment of bulk materials having closures for the discharge openings of the containers constrained to sliding movement for a part of their travel and having swinging and sliding movement for the remainder of their travel, the containers adjacent the discharge openings being constructed and associated with the closures to automatically insure sliding movement at the end of the swinging and sliding movement.

With these and other objects in view which will become clear as the description proceeds the invention comprises the novel structure and combination of parts hereinafter described and particularly pointed out and defined in the appended claims.

In the drawings forming part of this specification:

Fig. 1 is a view partly in section and partly in elevation of the lower portion of a container embodying the invention.

Fig. 2 is a view taken along line 2—2 of Fig. 1 looking in the direction of the arrows.

Fig. 3 is a vertical section taken on line 3—3 of Fig. 2.

Fig. 4 is a section taken on line 4—4 of Fig. 1.

Fig. 5 is a vertical section taken on line 5—5 of Fig. 2.

Fig. 6 is a horizontal section taken on line 6—6 of Fig. 5.

Fig. 7 is a diagrammatical illustration of the movement of the closure.

Referring to the drawings wherein a preferred

embodiment of the invention is illustrated, there is disclosed the lower portion of a shipping container including the discharge opening for the container, the closure for the discharge opening and the mechanism by means of which the closure is actuated. The container, indicated generally by the reference numeral 10, embodies the side sheets 11 and 12, corner angles 13 and 14 to which the side sheets are secured as by means of rivets, and slope sheets 15 and 16 converging downwardly and spaced apart, as more clearly shown in Fig. 1 of the drawings, to provide in part a discharge opening 17. These slope sheets are secured as by means of rivets 18 and 19 to the side sheets 11 and 12. The lower portion of the container is reinforced by means of angle members 20 and 21 preferably riveted to the side sheets and by means of angle members 22 and 23 secured to and extending between the corner angles 13 and 14. The angle members 20, 21, 22 and 23 provide a rectangular base for the container.

The lower slope sheet 16, as more clearly shown in Fig. 1 of the drawings, extends downwardly beyond the slope sheet 15. To the lower margin of the latter slope sheet there is secured as by means of rivets an angle member 24 having one leg 25 extending below the slope sheet in parallel relationship to the slope sheet 16. As more clearly appears from Fig. 4 of the drawings, the angle member 24 extends between the side sheets 11 and 12 and the ends of the leg 25 are coped, as indicated at a, b, c, d and e to permit of the attachment of brackets 26 and 27 hereinafter more fully described. Converging slope sheets 28 and 29 cooperate with the slope sheets 15 and 16 to complete the discharge opening 17. Each of the slope sheets 28 and 29 is formed with a flange 33 secured respectively to the side sheets 11 and 12 of the container. Slope sheet 28 is provided with an upper flange 30 fastened to the leg 25 and a lower flange 32 secured to the slope sheet 16. Similarly, slope sheet 29 has upper and lower flanges 31 and 32 secured respectively to the leg 25 and slope sheet 16.

The side slope sheets 28 and 29 are flanged outwardly, as indicated at 34 and 35, these flanges being aligned with the cope in the leg 25 of the angle member 24 indicated by the line d. By this construction the material in the container is guided during discharge through the opening in the container.

The discharge opening 17 is controlled by means of a door 36 which are more clearly shown in Fig. 1 of the drawings, is preferably disposed

in closed position in parallel relationship to the slope sheet 15. The door 36 is preferably formed of sheet metal and is provided with a flange 37 at its upper margin which overlaps the leg 25 of angle member 24 when the door is in closed position and cooperates with an angle 38 secured to the leg 25 to exclude the elements. Flanges 39 and 40 are formed along the side marginal portions of the door. These flanges when the door is in closed position overlap the outwardly extending flanges 34 and 35 of the side slope sheets 28 and 29 as more clearly appears in Fig. 4 of the drawings. The door is reinforced along its top and side margins by means of angle members 41, 42 and 43 and along its lower margin by means of a Z-shaped member 44 which cooperates with the flange 45 of a Z-shaped member 46 fastened to the slope sheet 16 in order to weather-proof the lower edge of the door and prevent the escape of material from the container. These function of the cooperating Z-bars 44 and 46 are aided by the cooperation between the lower edge of the door and the Z-shaped member 46 as more clearly appears from Fig. 3 of the drawings.

Weather-proofing of the side edges of the door 36 is secured by the relationship between the flanges 39 and 40 provided on the door and the outwardly extending flanges 34 and 35 of the side slope sheets 28 and 29. This weather-proofing is had by the engagement between the door and the edges of the flanges 34 and 35 and by the relationship between the door flanges 39 and 40 and angle members 47 and 48 fastened to the outwardly extending flanges 34 and 35.

According to the invention, the door in its initial opening and final closing movements is constrained to sliding movement so that controlled discharge of smaller particles of material may be secured. Resistance to outward pressure on the lower portion of the closure by the material in the container is obtained by means of substantially Z-shaped members 49 and 50 fastened as by means of rivets to the side slope sheets 28 and 29 and cooperating substantially Z-shaped members 51 and 52 fastened to the lower corners of the door.

The Z-shaped member 52 is retained between the Z-shaped member 50 and a channel shaped member 53 extending between and secured to the member 50 and the flange 35 of the slope sheet 29. The Z-shaped member 51 on the opposite side of the door is retained by a similar construction.

The invention provides mechanism for actuating the door. To this end the brackets 26 and 27 are secured as by means of rivets to the side sheets 11 and 12 of the container. These brackets comprise attaching flanges 54 and 55 and attaching flanges 56 and 57. Intermediate these attaching flanges the side sheets 11 and 12 are cut away as indicated at 58 and 59 to permit access to the opposite ends of an operating shaft 60. The ends of this shaft extend through elongated openings 61 and 62 formed by the flanges 63 and 64 and by the flanges 65 and 66. The flanges 63 and 65 project from inwardly directed flanges 67 and 68 on the brackets 26 and 27 and the flanges 64 and 66 project from inwardly directed flanges 69 and 70 provided on the brackets. The flanges 67 and 68 are formed with teeth 71 and 72 and the inwardly directed flanges 69 and 70 form runways 73 and 74.

The shaft 60 swingably supports the door 36 which is mounted upon the shaft by means of

bearings 75 and 76 fastened to the door. Pinions 77 and 78 arranged to mesh with the teeth 71 and 72 on the brackets 26 and 27 are secured upon the shaft for rotation therewith. The shaft 60 carries rollers 79 and 80 rotatably mounted thereon and seated upon the runways 74 and 75.

To open the door 36 a crank may be slipped upon either end of the shaft 60 in order to impart rotation thereto. The shaft is rotated so that the pinions 77 and 78 will move along the inwardly directed flanges 67 and 68 of the brackets by reason of the meshing of the pinions with the teeth 71 and 72 formed on these flanges. This movement of the shaft carries the door to which it is secured by the bearings 75 and 76 with it. During the initial movement of the door, however, it is constrained to sliding movement by the cooperation between the flanges 39 and 40 on the door 36 and the angles 47 and 48 fastened to the flanges 34 and 35 of the slope sheets 28 and 29. Control of the initial movement of the door is thereby secured and where the load in the container is formed of materials of small size this control of the door movement provides control of the discharge of the load. As a consequence, any desired quantity of the load may be deposited at any indicated place since the flow of material from the container may be cut off at will.

Continued opening movement of the door disengages the door from the Z-shaped members 49 and 50 whereupon the rush of material from the container swings the door about the shaft so that rapid discharge of the material is obtained. The angularity of the door relative to the opening depends upon the engagement between the flanges 39 and 40 with the angles 47 and 48 and the position of the shaft 60.

To close the door the shaft 60 is rotated in the opposite direction. During the closing movement of the door it is engaged by the angles 47 and 48 so that as the shaft moves downwardly, as viewed in Fig. 1 of the drawings, these angles cause the door to swing about the shaft and assume a position which will insure sliding engagement between the Z-bar members 51 and 52 on the door with the Z-shaped members 49 and 50 on the slope sheets 28 and 29 during final closing movement of the door. When closed the door is held against the thrust of the material in the container by the Z-shaped members 49 and 50.

The movement of the door in opening and closing direction is diagrammatically illustrated in Fig. 7 of the drawings. The door and shaft are shown in closed position in full lines and are indicated by the reference character A. The door and shaft are illustrated by the dash and single dot lines after the door has completed its initial sliding movement, the door and the corresponding position of the shaft at this time being shown at B. The door is then disengaged from the guide means which are no longer capable of preventing swinging movement of the door about the shaft. Continued opening movement of the shaft and door is accompanied by swinging movement of the latter about the shaft, the degree of swinging movement being determined by the position of the shaft and the angles 47 and 48. As the shaft moves from B to C the door has swung to C and when the shaft has moved to D where it lies above the angles 47 and 48, the door is swung to its full open position at D.

As the load is discharged the door 36 will swing

in closing direction about the shaft 61 until it assumes a vertical position. The shaft is then rotated so that it moves downwardly as viewed in Fig. 1 of the drawings carrying the door with it. As the door proceeds to closed position its engagement with the angles 47 and 48 will cause it to swing about the shaft and automatically to assume the position shown by the dot and single dash lines. This insures engagement of the door with the Z-shaped means 49 and 50 as the shaft continues its downward movement.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A shipping container for bulk materials comprising a base, converging slope sheets spaced apart to provide a discharge opening above the base of the container, a closure for said discharge opening, means including a shaft upon which said closure is swingably mounted for actuating said closure and cooperating means on said container and closure above said base constraining said closure to sliding movement during initial opening and final closing movements, said shaft moving bodily during said sliding movement of said closure, said closure and actuating means being at all times above the base of said container.

2. A shipping container for bulk materials comprising opposed walls, downwardly converging slope sheets secured to and extending between said wall, a member secured to one of said slope sheets in spaced relation to the other of said slope sheets, inwardly converging slope sheets secured to said opposed walls, said latter slope sheets extending between and being fastened to said member and said downwardly extending slope sheet spaced from said member, all of said slope sheets defining a discharge opening, means secured to said inwardly converging slope sheets beyond said discharge opening, a swingably mounted closure for said discharge opening, said means engaging and supporting said closure against pressure of the material in said container and means for actuating said closure.

3. A shipping container for bulk materials having a discharge opening, a closure for said discharge opening, bodily movable means swingably mounting said closure, means on said container constraining said closure to sliding movement during initial opening and final closing movements, guide means on said container for supporting the lower portion of said closure against the thrust of the material in said container, said closure being capable of swinging movement when disengaged from said guide means, said first mentioned means swinging said closure about said bodily movable means during closing movement thereof into position to engage said guide means.

4. A shipping container for bulk materials having a base, a discharge opening above the base of said container, a closure for said opening, a creeping shaft, said closure being swingably mounted upon said shaft, means for operating said shaft and means on said container above said base constraining said closure to sliding movement during initial opening movement of said closure, said shaft moving bodily during said sliding movement of said closure, said clo-

sure and operating means being at all times above the base of said container.

5. A shipping container for bulk materials having a discharge opening, a closure for said opening, a creeping shaft, said closure being swingably mounted upon said shaft, means for operating said shaft, means on said container engaging said closure during closing movement to swing said closure about said shaft to said discharge opening, said means maintaining said closure against said discharge opening during the final closing of said closure.

6. A shipping container for bulk materials having a discharge opening, a closure for said discharge opening, means swingably mounting said closure, said means moving bodily in the opening and closing movements of said closure, and means on said container for swinging said closure about said first mentioned means to said discharge opening during bodily movement of said first mentioned means.

7. A shipping container for bulk materials having a discharge opening, a closure for said opening, a creeping shaft, said closure being swingably mounted upon said shaft, means for operating said shaft, means on said container restraining said shaft to straight line movement during opening and closing movements of said closure, means on said container for swinging said closure about said shaft to said discharge opening during closing movement thereof and before said closure reaches its final closed position, said latter means constraining said closure to sliding movement during final closing movement thereof.

8. A shipping container for bulk materials having a discharge opening, a closure for said opening, a creeping shaft, said closure being swingably mounted upon said shaft, means for operating said shaft, means on said container restraining said shaft to straight line movement during opening and closing movements of said closure, means on said container for swinging said closure about said shaft to said discharge opening during closing movement thereof and before said closure reaches its final closed position, said latter means constraining said closure to sliding movement during final closing movement thereof and means for securing said closure against the thrust of the material in said container when said closure is closed.

9. A shipping container for bulk materials having a discharge opening, a closure for said discharge opening, means swingably mounting said closure, said means moving bodily in the opening and closing movements of said closure, and means on said container for swinging said closure about said first mentioned means to said discharge opening during bodily movement of said first mentioned means, and means disposed beyond said discharge opening for supporting the lower portion of said closure against the pressure of the material in said container when said closure is closed.

10. A shipping container for bulk materials having a discharge opening, a closure for said discharge opening, means swingably mounting said closure, said means moving bodily in the opening and closing movements of said closure, and means on said container for swinging said closure about said first mentioned means to said discharge opening during bodily movement of said first mentioned means and before said closure reaches its final closed position, said second mentioned means constraining said closure to

motion of translation during final closing movement thereof.

11. A shipping container for bulk materials having a discharge opening, a closure for said discharge opening, means swingably mounting said closure, said means moving bodily in the opening and closing movements of said closure, and means on said container for swinging said closure about said first mentioned means to said

discharge opening during bodily movement of said first mentioned means and before said closure reaches its final closed position, said second mentioned means constraining said closure to motion of translation during final closing movement thereof, and means for securing said closure against the thrust of the material in said container when said closure is closed.

FRANK DITCHFIELD.
